UNITED STATES PATENT OFFICE

122,546

DESIGN FOR A DRESS ENSEMBLE

Irving Grobstein, New York, N. Y.

Application July 10, 1940, Serial No. 93,546

Term of patent 3½ years

To all whom it may concern:

Be it known that I, Irving Grobstein, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design.

Fig. 2 is a rear view of Fig. 1.

Fig. 3 is a front view of the dress member, and

Fig. 4 is the rear view thereof.

The characteristic feature of my design resides in the combination on the ensemble disclosed of the specific jacket member, which is trimmed as shown, in association with the specific dress section.

I claim:

The ornamental design for a dress ensemble, substantially as shown and described.

IRVING GROBSTEIN.
